AUTOMOBILE TRUNK

Filed Jan. 18, 1927

UNITED STATES PATENT OFFICE.

ALLAN J. McDougall, OF DENVER, COLORADO.

AUTOMOBILE TRUNK.

Application filed January 18, 1927. Serial No. 161,719.

This invention relates to a trunk to be attached and permanently carried by an automobile at the rear of the body thereof, and has for its principal object, the provision of 5 a trunk of this character, in which the automobile tools and repair parts may be carried so that they may be accessible without it being necessary to disturb the remaining contents of the trunk, and yet will be securely 10 locked in place and accessible only through the usual trunk locks.

Another object of the invention is to provide a lid construction for the trunk which will prevent dust and moisture from reaching 15 the contents.

A further object is to provide a carrier for the automobile tools which will be maintained by the trunk in a convenient position for the operator and which can be removed 20 from the trunk and carried to any desired point without disturbing the tools or the trunk contents.

A still further object is to provide a tool drawer construction provided with protective drains to prevent moisture from entering 25 the tool compartment.

Other objects and advantages reside in the detail construction of the invention, which is designed for simplicity, economy and efficiency. These will become more apparent 30 from the following description.

In the following detailed description of the invention, reference is had to the accompanying drawing which forms a part hereof. 35 Like numerals refer to like parts in all views of the drawing and throughout the description.

In the drawing:

Fig. 1 is a perspective view of my complete 40 automobile trunk.

Fig. 2 is a vertical longitudinal section through the same.

Fig. 3 is an enlarged detail cross section through one of the upper edges of the trunk 45 showing the contact between the lid and the trunk proper.

Fig. 4 is a cross section, taken on the line 4—4, Fig. 2.

Fig. 5 is a horizontal detail section, taken 50 on the line 5—5, Fig. 2.

Fig. 6 is a detail perspective section through the lid flange.

The invention comprises a trunk proper, designated in its entirety by the numeral 10, 55 having a lid 11 hinged at 12 and provided with any of the usual trunk draw bolt locks

13. The trunk 10 and the lid 11 are preferably formed of sheet metal, the trunk 10 being curved, as shown at 16, to conform to the contour of the back of the automobile. 60

A false bottom 14 is welded into the trunk at 20 below which a tool drawer 15 slides. The tool drawer 15 is provided with a concavity 17 extending through its length to allow it to pass the rear fender of the automobile as it is withdrawn from the trunk. The drawer 15 rests and slides upon a main trunk bottom 18 guided by angle iron guides 19 and stopped in the proper closed position by a suitable stop 33. The drawer is locked 70 in the closed position by means of a draw bolt 21 which slides vertically in a guide 22 in the trunk and a similar guide 23 in the drawer.

Along the top of the opening in the trunk 75 through which the drawer passes the trunk metal is turned upwardly forming a drain trough 24 which prevents water from entering the drawer. The sides of this opening are turned inwardly as shown at 25, Fig. 5, to 80 strengthen the opening edges and prevent the drawer from binding thereon.

The drawer 15 is relatively shorter than the length of the trunk and is provided at both ends with carrying handles 26 so that 85 it may be entirely removed from the trunk and readily carried to any desired point.

When the drawer is in position and locked by means of the draw bolt 21, the lid 11 and the locks 13 prevent access to the draw bolt 90 so that the tool drawer cannot be opened by an unauthorized person.

In Fig. 3 I have illustrated the detail construction of the joint between the trunk and the lid. This section is typical of the entire 95 upper edge of the trunk the position of the hinges 12 being indicated in broken line thereon. It is desired to call attention to this section and to Fig. 6 to illustrate the dust-proofing feature of the trunk. The metal of the lid 11 is turned downwardly around the lid edges to form a downwardly projecting flange 27. An angle-shaped strip of metal 28 is placed inside of this flange and the flange metal is then turned upwardly on the inner 100 face of strip 28, as shown at 29. This firmly locks the strip 28 in place and the strip 28 not only provides a stiffener for the lid flange, but serves to increase its thickness so as to give a better appearance to the article. 110

A strip of felt or similar compressible material 30 is now inserted in the angle of the

strip 28 as shown in Fig. 6 and the free edge of the strip is clamped against this felt, as shown at 31, firmly securing it in place.

The entire upper edge of the trunk is inset as shown at 32 to receive the lid flange, the upper edge of the trunk extending upwardly sufficiently far to contact with and compress the felt 30. This provides an efficient seal against the entrance of dust and moisture. 10 The long contact between the trunk and lid flange acts as a first seal and the contact between the trunk edge and the felt 30 provides a second seal.

Should it not be desired to use the strip 28, the lid flange may be turned backward on itself and then turned around the felt strip 30 forming in itself a lock for the felt strip as shown in Fig. 2. This method, however, does not provide a stiff, neat appearing flange and is more difficult to manufacture than the previously described form.

While a specific form of the improvement has been described and illustrated herein, it is desired to be understood that the same may be varied, within the scope of the appended

claims, without departing from the spirit of the invention.

Having thus described the invention, what I claim and desire secured by Letters Patent is:—

30

1. An automobile trunk comprising a container; a hinged lid for said container; a false bottom in said container; a drawer opening to one face of said container and adapted to slide below said false bottom; and a trough formed on the exterior of said container above said drawer to prevent moisture from entering the latter.

35

2. A trunk for an automobile comprising a container; a hinged lid for said container; a false bottom in said container; and a drawer opening to one face of said container and adapted to slide below said false bottom, said drawer having a concavity extending throughout its length to allow it to pass the 40 rear fender of said automobile.

45

In testimony whereof, I affix my signature.

ALLAN J. McDougall.
